UNITED STATES PATENT OFFICE.

WILLIAM B. SWAN, OF SEYMOUR, CONNECTICUT.

DISPLAY BOARD.

Application filed April 6, 1927. Serial No. 181,442.

This invention relates to an apparatus for displaying articles offered for sale, or samples, or advertisements or the like, and has for an object to provide a device of this character which will display the articles in a position where they may be easily examined, and may all be eventually examined from a single location.

It is also an object of the invention to provide a device of this character which will have a plurality of boards or panels for carrying the articles to be displayed, which boards or panels will be successively moved to a given position, which also at a given position will be turned through an angle of one hundred and eighty degrees to expose articles carried on opposite sides of the panel, and the movement of the panel will be such as to attract attention.

With the foregoing and other objects in view, I have devised the construction illustrated in the accompanying drawings forming a part of this specification. In these drawings:

Fig. 1 is a partial vertical section and partial front elevation of the device.

Fig. 1^a is a vertical central section on a plane through the centers of the supporting shafts showing how the elements are mounted, the central shaft being in elevation.

Fig. 2 is a transverse section substantially on line 2—2 of Fig. 1 showing the panels removed and the lower portion of the mechanism in elevation.

Fig. 3 is a transverse section substantially on line 3—3 of Fig. 1 showing details of the operating mechanism.

Fig. 4 is a similar view showing another position of this mechanism, and

Fig. 5 is an enlarged plan view of the means for turning the panels to reverse the same and expose the articles on the opposite sides thereof.

The device is mounted on a suitable support, such as a table 10, supported by suitable legs 11. Most of the mechanism is mounted on and above the top of the table, although a portion of the driving mechanism is mounted below this top. Mounted on the top of the table is a ring 12 having spaced upwardly extending flanges 13 and 14 forming a guide groove 15, and at the outer periphery of this ring is an upwardly extending sheet metal member 16 forming a finishing wall to enclose the mechanism and give a finished appearance.

Mounted to turn in the table is an upright shaft 17 surrounded by a tubular shaft 18 which is in turn surrounded by an outer tubular shaft 19. The shaft 17 projects below the top of the table and carries a gear 20 meshing with a pinion 21. This pinion is on a shaft 22 also carrying a worm gear 23 which meshes with a worm 24 driven by an electric motor 25.

Mounted on the top of the table and at substantially the center of the member 12 is a plate 26 forming a bearing for the shaft 17 and having a boss on the top forming a bearing for a movable cam plate 27. 70 Mounted above this cam plate is a ratchet plate 28 connected to the central boss or hub 29 of a spider having a plurality of arms 30. It is preferred to use ball thrust bearings between the members 26, 27 and 28 as 75 they give freer and easier operation. In the present showing there are five arms 30 one for each of the five panels 31. These panels are carried in grooved supports 32, there being a support for each panel, mounted to rotate in bearings 33 at the outer ends of the arms 30. These supports are grooved so that the panels can slide into them from the ends thereof making it a simple matter to insert or remove the panels. Each support preferably has two grooves, as shown, so that it may carry two panels, one facing in and the other out, on which the articles to be displayed are mounted. When mounted, however, the effect for a single support is 80 a single panel and a single panel may be used to carry the articles on the opposite faces thereof if desired. The upper ends of the panels are mounted in similar supports 34 pivotally mounted in bearings 35 in the 85 arms of a spider 36 similar to the lower spider. This spider is mounted on the outer shaft 19 so that it will rotate with the lower spider and they are also tied together by means of tie rods 37.

Connected to the pivot for the supports 32 and below the arms 30 is a member 38 carrying a pair of rollers 39 running in a groove 15 in the ring 12, so that as the spiders rotate and carry with them the panels and their supports, the panels will be held so that a given side will face outwardly. These rollers also cooperate with a special mechanism to reverse the panels by rotating them through one hundred and eighty degrees as 110 they pass a given point, say at the front of the machine. This reversing mechanism is

shown more clearly in Figs. 2 and 5. At the desired point in the guide ring 12 the inner flange 13 is offset inwardly, as shown at 40, the shape being preferably substantially V-shape. Mounted in this offset but spaced a suitable distance therefrom is a deflector 41 having inclined side walls substantially parallel with the sides of the offset 40, and therefore, form with the offset a substantially V-shaped offset comprising a continuation of the guide groove 15 in which the rollers 39 run. At the outer side of the block is a guide 42, and the outer flange 14 is omitted on the outside of this guide or it is bulged outwardly so as to provide a space for one of the rolls outside this guide. The deflector 41 is mounted for limited movement, as indicated by the dotted lines in Fig. 5. A convenient means of mounting this block is a stud 43 extending through an elongated slot 44 in the bottom wall of the ring 12. This stud and the inner wall of the guide 42 form guiding means for the movements of the deflector, and the ends of the slot limit its movements in opposite directions. A spring 45 tends to hold the guide in the full line position in Figs. 2 and 5, somewhat nearer the right hand side of the offset than the left hand side thereof.

It will be obvious that as the spiders rotate in the direction indicated by the arrow (A) in Fig. 2 the rollers 39 will run in the guide grooves 15. As this movement continues the forward roller 39^a will engage the rear inclined wall 46 of the deflecting block 41, as indicated in heavy dotted lines, Fig. 5. The movement of the roller will shift this block 41 to the left to the dotted line position and the inclined wall 46 will force the roller into the offset or upwardly, as viewed in this figure. This movement, of course, will swing this roller inwardly about the axis of the bearing 33 for the panel mount and will move the second or rear roller 39^b outwardly about this axis into the outer offset portion 47 of the groove 15 outside the guide 42. The forward roller 39^a must move along the inclined wall 46 of the deflector block to the apex thereof and then the spring 45 will shift this deflector block 41 back to its original full line position. The forward roller 39^a, therefore, cannot move back out the inlet side of the offset but must pass out the other side of the offset or through the groove formed by the offset and the front side 48 of the deflector block. The rollers 39^a and 39^b are now in the position shown by the dot and dash lines of Fig. 5 with what was the rear roller 39^b running outside the guide 42 somewhat ahead of what was the forward roller 39^a and which is now in the offset 40. Upon continued movement of the spider the wall 49 of the offset will force the roller 39^a outwardly and the roller 39^b inwardly so that they will continue in

the slot 15, but they are now reversed with the roller 39^b ahead. It will be apparent that during this movement the panel has been turned through an angle of one hundred and eighty degrees and the inner side is, therefore, exposed or looking outwardly while what was the outer side is now turned inwardly.

The spiders and the supports for the panels are rotated about a vertical axis with a step by step movement. For this purpose the ratchet plate 28 is provided with a plurality of equally spaced notches 50, the number of notches corresponding to the number of panels. Mounted on the cam plate 27 is a pivoted pawl 51 with its free end held by a spring 52 against the edge of the ratchet plate. A connecting rod or link 53 is pivoted at its opposite ends to the cam plate and an oscillating arm 54. This arm is mounted on a vertical shaft 55 carrying another arm 56 below the table top and this latter arm is connected by a link 57 to the gear 20. The cam plate 27 has a cutout 58 at one side cooperating with a slidable locking pin 59. The end of this pin is arranged to seat in any one of the notches 50, and a spring 60 tends to hold it in this position.

In operation, as the gear 20 is rotated by the motor the crank 61 will be rotated with it. This will swing the link 57 and the arm 56, the arm 56, however, being of such a length that it will not be given a complete revolution but will be given an oscillatory movement. As this arm is swung back and forth it will, of course, give a similar movement to the arm 54, and this arm through the link 53 will oscillate the cam plate 27. In Fig. 4 this arm 54 is shown in its extreme retracted position and the end of the pawl 51 has dropped into one of the notches 50 in the ratchet plate. In this position the edge of the cam plate 27 has engaged the inner end of the locking pin 59 and has moved it outwardly out of the notch in the ratchet plate. The ratchet plate is, therefore, unlocked and is free to move. Now as the gear 21 continues to rotate it will swing the arm 54 in the opposite direction or to the left, as shown in Fig. 4. This will swing the cam plate 27 in the clockwise direction, as indicated in Fig. 4, and will carry with it the ratchet plate through the action of the pawl 51, and will also carry with it the two spiders 30 and 36 carrying the display panels. When the arm 54 reaches the extreme left hand position shown in Fig. 3 the locking pin 59 may drop into a notch 50 in the ratchet plate under the action of the spring 60 because the cutout 58 in the cam plate is now in alignment with the pin. The ratchet plate and the spiders are now locked against rotation and will be held in this position while the arm 54 and the cam plate are again retracted or swung

outwardly to the position shown in Fig. 4. Thus it will be apparent the supporting spiders and the panels carried thereby will be rotated with a step by step movement.

5 Ordinarily the front position is at the bottom of Fig. 2, and therefore, it is preferred to locate the panel reversing mechanism just forwardly or to the right of this position so that the panels are reversed just prior to 10 their reaching the forward position.

I may also mount on the continuously rotating central shaft 17 a distinctive sign, name or other mark indicating the manufacturer or exhibitor, or any other matter 15 desired. In the present instance this sign comprises a swan 62 mounted on a supporting bracket comprising a base 63 and supporting arms 64 and 65. Between the arms 64 and 65 is a spacing block 66 which may 20 turn about the intermediate shaft 18, and below the arm 65 is a block 67 seated on the upper end of the shaft 19 and having a thrust bearing thereon. One of the upper arms 64 is clamped to the central shaft 17, 25 as by a nut 68, so that this support must rotate with this shaft. The support is preferably so adjusted that it will reach the forward position or the position over the forward panel at about the time this panel is 30 reversed although, of course, this is merely a matter of preference. The support carrying the swan will make one complete revolution for each step by step movement of the panels.

35 It will be apparent from the foregoing description that the panels, five in this instance, are all rotated as a unit bodily about an upright axis with a step by step movement, so that they are all moved to a given 40 position in succession and remain stationary in this position a given length of time so that the articles mounted on the panel may be inspected. Also it is apparent that during each step by step movement one of the 45 panels is reversed, exposing by this operation the articles carried on the opposite side of this panel and concealing the articles which were prior to this reversing movement on the outside of the panel. Therefore, 50 practically twice as many articles may be exhibited on this device as there could be if the panels were not reversed, and this reversing movement gives the moving element which attracts attention and interest 55 in these types of devices.

Having thus set forth the nature of my invention, what I claim is:

1. In a display board, a rotatable support, a plurality of panels for carrying articles 60 to be displayed pivotally mounted on the support, a guide rail having a guiding groove, a pair of guiding elements connected to each panel and both running in said groove, means to rotate the support, and 65 means in a given position in said guide rail

to cooperate with said guiding elements to reverse a panel as it moves past said position.

2. In a display board, a support mounted to rotate about an upright axis, means for rotating said support, a plurality of upright 70 display panels pivotally mounted on said support, a guide rail associated with the support having a substantially circular guide, a plurality of guiding elements connected to each panel and each cooperating with said 75 guide to maintain the panel in a given position relative to said support, and means at a given position to cooperate with the guiding elements to reverse the panels and operated by movement of the panel with its support. 80

3. In a display board, a support mounted to rotate about an upright axis, means for rotating said support with a step by step movement, a plurality of upright display 85 panels pivotally mounted on said support, a guide rail below the support having an endless guide groove, a plurality of guiding elements connected to each panel and running in said groove to maintain the panels in given positions, and means at a given location in said groove to engage said guiding elements and cooperate therewith to reverse the panels as they pass by said location. 90

4. In a display board, a support mounted to rotate, a plurality of panels pivotally 95 mounted on said support, means for rotating the support, a guide rail adjacent the support having a guide groove with an offset therein, spaced guiding elements connected to the panels and running in said 100 groove, a movable guide block mounted in the offset and provided with inclined side walls, said block being in alignment with the groove so that one of the side walls will be engaged by the forward of said elements 105 and be deflected laterally thereby to turn the panel on its pivot, and a spring to shift the block when the element reaches the apex of the block to cause the element to pass on the other side of the block. 110

5. In a display board, a support mounted to rotate, a plurality of panels pivotally mounted on said support, means for rotating the support, a guide rail adjacent the support having a guide groove with a laterally extending substantially V-shaped offset therein, a guide forming a curved offset in the opposite direction, spaced guiding elements connected to each panel and running in said 115 groove, the first offset having inclined side walls in alignment with the groove one of which is in position to engage the forward element and deflect it laterally while the other element passes through the other offset and thus reverses the panel. 120

6. In a display board, a support mounted to rotate, a plurality of panels pivotally mounted on said support, means for rotating the support, a guide rail adjacent the support having a guide groove with a laterally 125 130

extending offset provided with inclined walls on its opposite sides, a movable guide block having inclined walls on its opposite sides substantially parallel with those of the offset, said block being mounted for limited movement longitudinally of the groove, spaced guiding elements connected to each panel and running in said groove, a spring tending to hold the block nearer one side of the offset than the thickness of a guiding element, the corresponding side wall of the block being arranged to engage the forward element and deflect it into the offset to turn the panel on its pivot, the other wall of the offset being in position to engage said element to move it back into alignment with the groove, and a guide for the other element during the turning movement.

7. In a display board, a rotatable support, means for rotating the support, a plurality of display panels pivotally mounted on the support, a pair of guide elements connected to each panel, a guide having a guiding groove in which said elements run, said groove having one wall laterally offset, a

block mounted for limited movement longitudinally of the groove and having inclined side walls substantially parallel to those of the offset, the forward wall of the block being in alignment with the groove to engage the forward guiding element and force it laterally into the offset, said block being adapted to yield to permit this movement, and a spring to shift the block in the opposite direction when the element reaches the inner end thereof so that the element must pass to the other side of the block.

8. In a display board, an upright continuously rotating shaft, a support mounted to rotate about said shaft, means to rotate the support with a step by step movement and arranged to give the support one of said movements for each revolution of the shaft, a symbol support mounted to move with said shaft, a plurality of display panels pivotally mounted on the first support, and means operated by each movement of said first support to reverse one of said display panels.

In testimony whereof I affix my signature.

WILLIAM B. SWAN.
